UNITED STATES PATENT OFFICE.

ERNEST L. GALE, SR., OF YONKERS, NEW YORK, ASSIGNOR TO OTIS ELEVATOR COMPANY, OF JERSEY CITY, NEW JERSEY, A CORPORATION OF NEW JERSEY.

MOTOR-ACCELERATING DEVICE.

1,064,205.

Specification of Letters Patent. Patented June 10, 1913.

Application filed November 9, 1909. Serial No. 527,096.

To all whom it may concern:

Be it known that I, ERNEST L. GALE, Sr., a citizen of the United States, residing at Yonkers, in the county of Westchester and State of New York, have invented a new and useful Improvement in Motor-Accelerating Devices, of which the following is a specification.

My invention relates to alternating current resistance cut-outs and has for one of its objects the provision of practical, positive and efficient means for controlling the acceleration of alternating current motors used for operating elevators or for other purposes, and also for accelerating direct current motors.

Generally speaking my invention consists of the combination of mechanical with electrical means for effecting the acceleration of alternating current motors.

Other objects of the invention and the various features of novelty will appear hereinafter.

The combinations of elements which are considered as new are set forth in the appended claims.

In the accompanying drawings, Figures 1 and 2 illustrate the combined elements used in my invention; Fig. 3 is a wiring diagram of electrical circuits for a typical alternating current push-button elevator system, together with my invention. Although the arrangements of circuits herein illustrated are based on an arrangement of an alternating current push-button elevator system of control, my invention could be readily applied to any system where automatic acceleration of the motor is desired.

Referring to Fig. 2, a sprocket wheel 10 is keyed or otherwise securely fastened on the shaft 1 and the latter is driven by means of the sprocket chain 11 (Fig. 3) and sprocket wheel 13 which is keyed on the winding drum shaft 12. Substantially mounted on the face of the drum 2 are the contacts *a*, *b*, *c*, *a'*, *b'* and *c'*. Integral with the drum 2 is a casing 20 which forms suitable supports for the spring 14 and pawl 5.

The stationary contacts A, B and C engage with the contacts *a*, *b* and *c*, or *a'*, *b'* and *c'*, depending on the direction of rotation of the drum 2. The leads 17, 18 and 19 make connections from the stationary contacts C, B and A, to the accelerating magnet

windings. A weight 44 for centering the drum 2 is secured to the latter by the bracket 43.

In the casing 20, which is shown in section in Fig. 1, the pawl 5 is guided in the slot 15 and is forced downwardly by the spring 60 14. The driving gear 3 is keyed or otherwise securely fastened to the shaft 1, and is engaged by the pawl 5 to rotate the drum 2. A release disk 4 is free to rotate on the shaft 1 and is held in position by the pivoted bracket 6 and lever 7, and serves to hold the pawl 5 out of engagement with the driving gear 3. A projection 24 on the disk 4 fits tightly into the slot 25 and keeps the disk 4 from rotating. The cam surfaces 37 70 and 37' on the disk 4 serve as positive knock-outs for the pawl 5, and an oblong slot 21 in the disk 4 allows the latter to lower when the lever 7 is released by the weighted core 29 of the automatic switch G being lifted, 75 thereby causing the spring-pressed pawl 5 to engage with the driving gear 3 to rotate the drum 2.

A primary mover rocking lever 7 is pivoted at 23 to the bracket 8 and a slot 26 is provided in said lever through which the core rod 27 is adapted to pass. A weight 28 secured to the lever 7 serves to insure the lowering of the left-hand arm of the lever 7 when the weighted core 29 of the automatic 85 switch G is lifted, said weighted core 29 resting on the knob 33 of the lever 7. A cushion stop 30 for the lever 7, preferably made of rubber or some resilient material, is substantially supported on the core rod 27. 90 The position of the cushion stop 30 may be adjusted by means of a nut 31' threaded on the rod 27, a lock nut 31 also being provided. Secured to the bottom of the automatic switch core 29 is a weight 32 which 95 rests on the knob 33 of the lever 7. It is seen that when the automatic switch G is open its weighted core 29 causes the drum 2 to be in a non-operative position, by reason of the pawl 5 being held out of engagement 100 with the gear 3 by means of the disk 4.

The final accelerating magnet H is provided with the contacts 34 and 35 which are adapted to complete a holding circuit for magnet H, when contact 34 is moved upwardly by the core 36 to engage the contact 35.

The function and operation of the various

parts shown in Figs. 1 and 2 will now be described.

Referring to Fig. 1, the final accelerating magnet H and the automatic switch G are shown open, this being their normal position when the motor is ready to be started. The primary mover lever 7 is acted upon by the weighted core 29 of the automatic switch G at the knob 33, and holds the disk 4 in its upward position with the bottom of its slot 21 in contact with the shaft 1, likewise holding the pawl 5 up and out of engagement with the driving gear 3, so that even if the gear 3 which is keyed to the shaft 1, is rotated, the drum 2 will not rotate. When the automatic switch winding 77 is energized the weighted core 29 is drawn upwardly, thereby releasing the lever 7 and allowing it to rock with the aid of the weight 28. When this weight 28 rocks the lever 7, it lowers the disk 4 so that the top of the slot 21 is against the shaft 1, thereby allowing the spring pressed pawl 5 to engage with the driving gear 3. A positive connection is now made for the drum 2, from the driven shaft 1, gear 3, pawl 5 and drum 2, and said drum is ready to be rotated when motor starts. We will say the shaft 1 is rotated in a clockwise direction, looking at Fig. 2 in the direction of the arrows 38-38. As the drum 2 rotates, contacts a and C will engage first thereby making a circuit for the winding 39 of the first resistance cutout magnet. As the drum rotates further the contacts b and B will be brought together just before the contacts a and C are separated, thereby making the circuit for the second resistance cut out winding 40 and then dropping the first magnet E. On further rotation of the drum, contacts a and A engage, and contacts b and B will separate, thereby breaking the circuit for the second magnet F and making a circuit for the winding 41, which in this case is the last resistance cutout magnet H. When the circuit for the last accelerating magnet H is closed, the contact 34 is operated by the core 36 to engage with contact 35, to make a self-holding circuit for the magnet H. The last accelerating magnet H is made self-holding so that when the pawl 5 is knocked out of engagement with the gear 3, thereby allowing the drum to center itself by means of the weight 44, the circuit for the winding 41 will still be made when the contacts a and A are disengaged. When the drum 2 has rotated far enough to make the circuit for the final accelerating magnet H, the resistance now being all cut out, it is evident that the drum should be reset to be in a position to operate when the motor is again started. The resetting operation is accomplished in the following manner:—When the drum 2 has rotated into position to bring the contacts a and A to

gether, and close the circuit for the magnet H, the latter lifts its core, carrying with it the lever 7 and the disk 4. The disk 4 lifts the pawl 5 out of engagement with the gear 3 and permits the drum to center itself by means of the centering weight 44. During this movement of the drum, the pawl 5 slides on the disk 4 and is thereby prevented from reengaging the gear 3, the disk 4 being held up during such movement by the magnet H. It will be understood that the holding circuit through the contacts 34, 35, maintains the magnet H energized at this time. The cam 37 may partially retract the pawl 5 before the magnet H is excited. The cam may of course be so formed that it will not be brought into position to operate until after the circuit for the magnet H has been closed, or said cam may commence to lift the clutch member 5 earlier in the rotation of the drum. The dropping of the automatic switch G also acts as a knockout for the pawl, in case of the elevator car not having traveled far enough to effect the operation of the last accelerating magnet. When the automatic switch G drops the weighted core 29 strikes on the knob 33 of the lever 7, thereby causing the disk 4 to knock the pawl 5 out of engagement with the driving gear 3, and allowing the drum 2 to center itself, in position to be operated again when the motor is operated. It is to be noted that under certain circumstances I have three different means for effecting the release of the pawl 5, but in case of the complete operation of the drum to effect the operation of all the accelerating magnets, I claim the disk 4 as my positive knockout.

Referring now to Fig. 3, I show my invention applied to an alternating current push button elevator system. It will not be necessary to go into details of the operation of the various parts shown in the push button system, as it only repeats well known features which are used in a typical alternating current push button system. I will first designate the parts shown in Fig. 3 which have not been described in Figs. 1 and 2. The motor M receives current from the means, through the main line switch S, the reversing switch J or K, and the automatic switch G. The accelerating magnets E, F and H are provided with suitable connections from the contact drum 2 and are adapted to short circuit portions of the starting resistance R. The elevator control system comprises: hall push buttons d, d', d'', car push buttons e, e', e'', car safety switch m, gate contact n, "up" floor controllers f, "down" floor controllers g, door contacts h, h', h'', floor magnets k, k', k'', non-interference magnets 45 and 46. The elevator car C may be driven by any suitable means, but in this instance I have shown a typical worm geared elevator installation. A

counterbalance weight W is suspended in the ordinary manner. A support 48 is provided for the slate board 47 upon which are mounted various magnets and switches diagrammatically shown, and for the shaft 1 upon which various parts shown in Figs. 1 and 2 are mounted. An electromagnetic brake B is connected to the main leads of the motor M. A sprocket wheel 13 on the drum shaft 12 drives the sprocket wheel 10 by means of the chain 11. The limit switches, l and l' are located at the upper and lower limit of travel of the elevator car C.

15 The operation of the apparatus shown in Fig. 3 is as follows:—The system shown is arranged for three floors, but an installation for any number of floors is similarly arranged. As shown in Fig. 3 the car is at the second floor landing and the floor controller contacts f and g will be in position as shown when the car is at said landing. Now if it is desired to go to the next floor above, the push button e'' in the car is pressed. 20 This makes a circuit for the floor controller magnet k'', which circuit may be traced as follows,—from the main wire 84, through conductors 49, 51, door contacts h'', h', h, wire 43, gate contact n, car safety switch m, wire 54, back contacts 56, 57, wire 58, back contacts 60, 59, wire 61, back contact 62 of the non-interference magnet 45, wire 63, magnet coil 64 of the relay magnet 46, wire 65, car push button e'', wire 66, floor magnet k'', 25 wire 67, contact 68, wire 69, contact 70, wire 71, floor controller switches 72, 73 and wire 74 to junction 75. This circuit being through the floor magnet k'', the latter is operated to bring the contacts 81 and 80 together and establish a circuit through a reversing switch magnet as will presently be pointed out. The push button circuit just traced also includes the relay magnet 46 and the latter is operated to establish a circuit 30 as follows: from the mains 84, through wires 49, 51, door contacts h'', h', h, wire 53, to junction 53', from thence through wire 52, noninterference magnet 45, contacts 68', 68, wire 69, contact 70, wire 71, floor controller switches 72, 73 and wire 74. This circuit includes the non-interference magnet 45, which operates to separate the back contacts 62, and to engage the contacts 70', 71', thus establishing a self-holding circuit for 35 the non-interference magnet 45, that is, the circuit from the junction 53' is through the magnet 45 and contacts 70', 70, independently of the relay 46. The non-interference magnet 45 having separated the contacts 62, 40 there can be no interference from the operation of the landing push button switches d, d'', as the circuit for these switches is open at the contacts 62.

The operation of the floor magnet k'' establishes a circuit for the magnet of the

reversing switch J as follows: from the main 45, through wires 49, 51, door contacts h'', h', h, wire 53, contact n, car safety switch m, wire 54, to junction 54', from thence through winding 76 to the reversing switch J, wire 76', back contacts 60' on reversing switch K, wire 61', floor controller switch 73', wire 80', contacts 80, 81, floor magnet k'', wires 67, 69, 71, switches 72, 73, wire 74, to junction 75. The portion of this circuit between the junction 54' and the contact 81 is in parallel 50 with a like portion of the pushbutton circuit including the back contacts 56, 57 and 59, 60, of the reversing switches, the magnet 64 and the pushbutton switch e''. The reversing switch magnet 76 is therefore in parallel 55 with the magnet 64 until the latter is deenergized either by releasing the pushbutton or by the opening of the back contacts 56, 57 on the reversing switch. The circuit 60 through the reversing switch magnet 76 forms a holding circuit for the magnet k''. The magnet 76 being energized, the reversing switch J closes and establishes a circuit 65 for the potential switch G'. The circuit for the winding 77 is from the main wire 82, through the winding 77, wire 83, limit switches l and l', and wire 74 to the main wire 84. The main switch S, reversing switch J and potential switch G now being 70 closed, complete a circuit to the stator of the motor M and to the brake B, and the motor starts to rotate at slow speed, all of the starting resistance R being in circuit 75 with the rotor of the motor. The automatic switch G operating to close its contacts, allows the weight 28 to lower the adjacent end of the lever 7, thereby lowering the disk 4 and releasing the pawl 5 to engage with the gear 3, thus making a positive connection 80 for the drum 2 to be rotated when the motor starts. We will say that when the car is going up the drum 2 will rotate in such a direction as to cause the contact e on the drum to engage with the stationary contact C, thereby completing a circuit for the winding 39, from wire 84, through wire 16, contacts e and C, wire 17, winding 39, wire 42, to motor lead 86. The coil 39 being energized causes the contact disk 85 to engage 85 with the contacts 79, 79' and 79'', thereby short circuiting a portion of the starting resistance and increasing the speed of the motor. As the drum 2 continues to rotate it brings the contacts b and B into engagement 90 and completes a circuit for the winding 40 from wire 84, through wire 16, contacts b and B wire 18, winding 40, wire 42 to motor lead 86, thereby short circuiting an additional portion of the starting resistance R 95 and causing the motor to further increase its speed. Upon further rotation of the drum it engages contacts a and A, making a circuit 100 for the winding 41, from wire 84, through wire 16, contacts a and A wire 19, 105 110

winding 41, wire 42 to motor lead 86, thereby operating the last accelerating magnet H to short circuit the last step of the resistance R and allowing the motor to run at full normal speed. The drum 2, after being rotated far enough to effect the operation of all the resistance cut-outs is released, either by the operation of the last accelerating switch H or by the co-operation therewith of the cam surface 37 or 37' of the disk 4 which rides the pawl 5 out of engagement with the gear 3 as hereinbefore, thereby allowing the drum 2 to center itself on the shaft 1 ready to be operated when the motor is again started. It is to be noted that when the weight 44 causes the drum to center itself, the contacts *a* and A are disengaged, thereby breaking the circuit for the last accelerating magnet winding 41. But the magnet H is provided with the contacts 34 and 35 which make a holding circuit for the winding 41, from wire 84, by means of wires 16, 43, contacts 34, 35, winding 41, wire 42 to motor lead 86.

25 The magnet H and the automatic switch G being co-acting parts for the lever 7, it is to be noted that when the magnet H is in its operative position, it acts as a hold-up for the lever 7 and its adjacent parts and when 30 the car has reached the desired floor, the floor contacts *f* are automatically operated to open the circuit for the reversing switch and floor controller magnets, thereby breaking the circuit for the last accelerating magnet H and the winding 77 of the automatic switch G and causing them to open. After 35 the magnet H drops, it no longer acts as a hold-up for the lever 7, but the automatic switch G now acts as a hold-up for the lever, by the weighted core 29 of the potential switch resting on the knob 33 of the lever. The reversing and automatic switch contacts now being open, cuts off the supply of current, and consequently 40 the brake is applied, the motor is stopped, and the parts are ready to be operated when the motor is again started. The above operation is for the upward travel of the car, but the principle and operation of my invention will be the same for the downward travel with the exception that the drum 2 will be rotated in the opposite direction.

45 While I have shown and described my invention as embodied in an electric elevator system and in a circuit controlling device, the same may have a wide application, furthermore it is obvious that various modifications could readily be made in the application 50 herein shown and described without departing from the spirit and scope of my invention, and for this reason I desire not to be limited to the precise construction and arrangement of parts as disclosed.

55 60 65 65 What I claim as new and desire to have

protected by Letters Patent of the United States is:—

1. The combination with an electric motor, of accelerating mechanism therefor comprising a contact drum, positive driving connections between said drum and the motor, circuits controlled by said drum and controlling the operation of the accelerating mechanism, and means for disconnecting the drum from the motor when the accelerating mechanism has operated to accelerate the motor.

2. The combination of an electric motor, accelerating mechanism comprising a contact carrying device controlling the accelerating mechanism, positive means for operating said device during the acceleration of the motor, and means for automatically disconnecting said device from the motor.

3. The combination of an electric motor, sectional starting resistance therefor, a contact device controlling short circuits for the sections of resistance, means for positively operating said device and effecting a short-circuiting of the resistance as the motor accelerates, and automatic means for disconnecting said device from the motor.

4. The combination of an electric motor, accelerating mechanism comprising a series of switches and a device for effecting the operation of the switches, gearing comprising a clutch between the said device and the motor, and means for automatically opening the clutch after the operation of the said switches.

5. The combination of an electric motor, sectional starting resistance, a rotatable drum, switches operated by the rotation of the drum and controlling the starting resistance, a clutch forming a positive driving connection between the drum and the motor, and means for automatically operating said clutch to disconnect the drum from the motor.

6. In combination, an electric motor, accelerating mechanism comprising a mechanically operated device, gearing comprising a clutch between the motor and said device, a switch in the main circuit of the motor, and means operated by said switch for controlling said clutch.

7. In combination, an electric motor, accelerating mechanism comprising a mechanically operated device, gearing comprising a clutch between the motor and said device, a switch in the motor circuit, and an electromagnet connected to operate said switch and controlling the operation of the clutch.

8. In combination, an electric motor, accelerating mechanism comprising a contact drum, gearing comprising a clutch between the said drum and the motor, a potential switch, and a potential switch magnet controlling the operation of said drum.

9. The combination of an electric motor, accelerating mechanism comprising a mechanically operable device, a clutch between said device and the motor, a potential switch and magnet, and means controlled by said magnet to operate said clutch and disconnect the said device from the motor when the potential switch is deenergized. 16. The combination with an electric motor, of sectional starting resistance, switches for short-circuiting said resistance, electromagnets for operating said switches, a rotary contact drum, contacts associated therewith and operable to close the circuits for the magnet windings of said electromagnets in succession, driving connections between the contact drum and the motor and comprising a switch, and a device operable by the last electromagnet of said series to disconnect the clutch members. 70
10. The combination of an electric motor, accelerating mechanism comprising a mechanically operable device, a potential switch and magnet, and means operated by said magnet to effect an operating connection between said device and the motor when the potential switch magnet is energized. 17. The combination with a driving shaft, a contact drum loosely mounted thereon, clutch members carried by said drum and shaft respectively, an electromagnet having a circuit controlled by said drum, and means operated by said electromagnet to disconnect the clutch members. 75
11. In resistance cut-out mechanism, the combination of a rotatable drum, electrical contacts on the drum, means for rotating the drum, a device for engaging the drum with said rotating means, means for automatically disengaging the drum from said rotating means, sectional resistance, fixed electrical contacts and connections, and electro-responsive devices actuated when the drum rotates and connects the contacts with the fixed contacts and operative thereupon to short-circuit portions of the sectional resistance. 18. The combination with a shaft, of a contact carrying device loosely mounted thereon, clutch members carried by said shaft and said device respectively, an electromagnet having a circuit controlled by said device, means operated by said electromagnet to disconnect the clutch members, and a device forming a positive means for disconnecting the clutch members independently of said electromagnet when the said contact device is rotated through a predetermined angle. 80
12. The combination of an electric motor, accelerating mechanism comprising a series of electromagnets, a device operable to close circuits for said magnets in succession, driving mechanism comprising a clutch between the motor and said device, and means operated by the last electromagnet in said series to operate the clutch and disconnect said device from the motor. 19. The combination of a drive shaft, a contact drum loosely mounted thereon, a clutch wheel secured to the shaft, a clutch member carried by the contact drum and movable into and out of engagement with said clutch wheel, and a stationary member co-operating with said clutch member to disengage it from said clutch wheel. 100
13. The combination of an electric motor, accelerating mechanism comprising a series of accelerating magnets, a rotary contact device operable to successively close the circuits for said magnets, a clutch forming a positive driving connection between said device and the motor, and means operated by one of said electromagnets to disconnect the clutch members. 20. The combination with a drive shaft, of a contact drum mounted thereon, a clutch member secured to the shaft, a clutch member carried by the drum, a cam disk, an electromagnet, and means operated by said electromagnet to move said cam disk into position to disengage the clutch members, said cam disk being formed to disengage the clutch members independently of the electromagnet when the contact drum has reached a predetermined position. 105
14. The combination of an electric motor, accelerating mechanism therefor comprising a rotary contact device, a clutch forming a positive driving connection between said contact device and the motor, and positive means for disconnecting the clutch when said contact device has been rotated through a predetermined angle. 21. The combination with an electric motor, of accelerating apparatus comprising a rotatable contact carrying member and a series of accelerating magnets, a driving connection between the motor and said contact carrying member comprising a clutch, means operated by one of said electromagnets to disengage the clutch members, an electromagnetic potential switch, means operated by the potential switch magnet to hold the clutch members disengaged while the potential switch is opened, and means independent of said magnets for disengaging the clutch members when the contact drum is rotated in either direction from its normal position. 115 120 125 130
15. The combination with an electric motor, of accelerating mechanism comprising a series of electromagnets, a contact drum controlling the circuits for said magnets, driving connections between said drum and the motor comprising a clutch, means operated by one of said electromagnets for disconnecting the clutch, and a mechanical device for positively disconnecting the clutch independently of said electromagnet.

22. The combination with an electric motor, of sectional starting resistance for the motor, resistance cut-out mechanism comprising a rotatable drum, drum contacts, fixed electrical contacts to correspond therewith, mechanical connections between the motor and the drum for rotating the drum at a speed proportional to that of the motor, electro-magnets successively energized as the drum is rotated, means for short circuiting sections of the starting resistance as the electro-magnets are energized, and means for automatically returning the drum to its initial position. 5
23. The combination with an electric motor, of sectional starting resistance for the motor, resistance cut-out mechanism comprising a rotating shaft, a contact drum free to rotate about the said shaft in either direction, fixed electrical contacts arranged to correspond with the drum contacts, mechanical means for rotating the contact drum in the same direction as the shaft, electro-magnets successively energized as the contact drum is rotated, means for short circuiting sections of the starting resistance as the electromagnet are energized, and automatic means for returning the contact drum to its initial position and holding the same stationary during the continued rotation of the said shaft. 10
24. The combination with an electric motor, of starting resistance for the motor, resistance cut-out mechanism comprising a rotatable shaft, means for positively driving the shaft from the motor, a contact drum rotatably mounted on the shaft, fixed contacts to connect with the drum contacts when the drum is rotated, electro-magnets energized when the drum is rotated, and a lever operative to permit the drum to rotate as soon as the motor is started. 15
25. The combination with an electric motor, of starting resistance for the motor, resistance cut-out mechanism comprising a rotatable shaft, means for positively driving the shaft from the motor, a contact drum rotatably mounted on the shaft, fixed contacts to connect with the drum contacts when the drum is rotated, electro-magnets energized when the drum is rotated and operative to alter the starting resistance, and a lever operative to effect the rotation of the drum as soon as the motor is started. 20
26. The combination with an electric motor, of starting resistance for the motor, resistance cut-out mechanism comprising a rotatable shaft, means for positively driving the shaft from the motor, a contact drum rotatably mounted on the shaft, fixed contacts to connect with the drum contacts when the drum is rotated, electro-magnets energized when the drum is rotated and operative to alter the starting resistance, and a weighted lever operative to permit the rotation of the drum as soon as the motor is started. 25
27. The combination with an electric motor, of starting resistance for the motor, resistance cut-out mechanism comprising a rotatable shaft, means for positively driving the shaft from the motor, a contact drum rotatably mounted on the shaft, fixed contacts to connect with the drum contacts when the drum is rotated, electro-magnets energized when the drum is rotated and operative to alter the starting resistance, a pivoted lever, means operated by the lever for holding the drum disconnected from the shaft and electro-responsive devices operative to release the pivoted lever and thereby effect the rotation of the drum in accordance with the shaft as soon as the motor is started. 30
28. The combination with an electric motor, of starting resistance for the motor, resistance cut-out mechanism comprising a rotatable shaft, a toothed wheel secured to the shaft, a drum rotatably mounted on the shaft, electrical contacts on the drum, fixed contacts to correspond therewith, electro-magnets energized when the drum rotates, and operative to short-circuit portions of the resistance, a pivoted rocking lever, electro-magnetic means for operating the said lever, and mechanism operated by said lever to connect the drum with the shaft and cause the drum to rotate. 35
29. The combination with an electric motor, of starting resistance for the motor, resistance cut-out mechanism comprising a rotatable shaft, means for positively driving the shaft, a contact drum rotatably mounted on the shaft, electro-magnets energized when the drum rotates and operative to short-circuit portions of the resistance, a pivoted rocking lever, means associated with the said lever for permitting the drum to be rotated by the toothed wheel, and an electro-magnet operative to effect the movement of the lever when the motor starts. 40
30. The combination with an electric motor, of starting resistance for the motor, resistance cut-out mechanism comprising a rotatable shaft, a toothed wheel secured to the shaft, a drum rotatably mounted on the shaft, electrical contacts on the drum, fixed contacts to correspond therewith, electro-magnets energized when the drum rotates and operative to short-circuit portions of the resistance, a pivoted rocking lever, a disk mounted on the rotatable shaft and associated with the rocking lever, means for engaging the toothed wheel to rotate the drum, and means for disengaging the toothed wheel. 45
31. The combination with an electric motor, of starting resistance for the motor, resistance cut-out mechanism comprising a rotatable shaft, means for positively driving the shaft as soon as the motor is started. 50

the shaft, a contact drum rotatably mounted on the shaft, electro-magnets energized when the drum rotates and operative to short-circuit portions of the resistance, a pivoted 5 rocking lever, a disk mounted on the rotatable shaft, means for raising or lowering the disk relatively to the shaft, and means for rotating the drum.

32. The combination with an electric motor, of starting resistance for the motor, 10 resistance cut-out mechanism comprising a rotatable shaft, means for positively driving the shaft, a contact drum rotatably mounted on the shaft, electro-magnets energized when the drum rotates and operative to short-circuit portions of the resistance, a pivoted rocking lever, a disk formed with a slotted opening for mounting the disk on the rotatable shaft, means for engaging the 15 drum with the toothed wheel to rotate the drum, and means in connection with the disk and the rocking lever for disengaging the drum from the toothed wheel.

33. The combination with an electric motor, of starting resistance for the motor, 20 resistance cut-out mechanism comprising a rotatable shaft, means for positively driving the shaft, a contact drum rotatably mounted on the shaft, electro-magnets energized when the drum rotates and operative to short-circuit 25 portions of the resistance, a toothed wheel connected to the shaft, a pivoted rocking lever, a device in connection with the contact drum operative to engage the toothed wheel to effect the rotation of the 30 drum, and means operable by said lever into and out of position to permit said device to engage the toothed wheel.

34. The combination with an electric motor, of starting resistance therefor, 35 resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, 40 and a disk operated by the lever and effective to permit the rotation of the drum when the lever is operated in one direction.

35. The combination with an electric motor, of starting resistance therefor, 45 resistance cut-out mechanism comprising a rotatable shaft, a toothed wheel secured to the shaft, a contact drum rotatably mounted on the shaft, electro-magnets energized in succession as the drum rotates and operative to 50 short-circuit portions of the resistance, a lever, electro-responsive means for permitting the lever to operate, means for engaging the toothed wheel to rotate the drum, and a disk operated by the lever and effective to permit the rotation of the drum and

to prevent the rotation farther than a predetermined point.

36. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, and a disk operative to permit the engaging means to rotate the contact drum, and said disk being provided with cam projections to effect the positive release of said engaging means.

37. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, and a slotted disk vertically movable and operative to permit the operation of the said engaging means, said disk being formed with cam surfaces for releasing the said engaging means when the drum has rotated a predetermined amount.

38. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever electro-responsive means for permitting the lever to operate, means for engaging the toothed wheel to rotate the drum, and a slotted disk operated by the lever to permit the operation of said engaging means.

39. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, a disk operated by the lever to permit the operation of the drum rotating means and to effect the release thereof when the drum has been rotated, and separate means for effecting the release of the drum rotating means.

40. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, a slotted disk permitting the operation of the tooth engaging means to rotate the drum when the lever is operated and preventing rotation of the drum further than a given amount, and means for returning the drum to its initial position after the drum has rotated the given amount. 70
41. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum; a disk operated by the lever to permit the engaging means to rotate the drum and to release the engaging means when the drum has been rotated a predetermined amount, and electro-responsive means for effecting the release of the engaging means before the drum has been rotated the predetermined amount. 75
42. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, a disk operated by the lever to permit the engaging means to rotate the drum and to release the engaging means when the drum has been rotated a predetermined amount, electro-responsive means for effecting the release of the engaging means before the drum has been rotated the predetermined amount, and means for returning the drum to its initial position whenever the engaging means has been released. 80
43. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a lever, electro-responsive means for permitting the lever to operate, means for engaging the toothed wheel to rotate the drum, a cam shaped disk operated by the lever to permit the operation of the engaging means and to disengage the same at a predetermined time, and means in connection with the last short-circuiting magnet for releasing the said engaging means as soon as the said magnet is energized. 85
44. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a weighted lever, an electro-magnet to release the lever when it is energized, a pawl for engaging the toothed wheel to rotate the drum, means operated by the lever to permit the engaging of the pawl and to disengage the same at a predetermined time, and an auxiliary contact for closing a retaining circuit through the last short-circuiting magnet as long as the electro-magnet which releases the weighted lever is energized. 90
45. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a weighted lever, an electro-magnet at one end of the lever to release the lever when the magnet is energized, means for engaging the toothed wheel to rotate the drum, a cam shaped disk operated by the lever to permit the operation of the engaging means and to disengage the same at a predetermined time, and means in connection with the last short-circuiting magnet for releasing the said engaging means as soon as the said magnet is energized. 100
46. The combination with an electric motor, of starting resistance therefor, resistance cut-out mechanism comprising a rotatable shaft, a toothed wheel secured to the shaft, a contact drum rotatably mounted on the shaft, electro-magnets energized in succession as the drum rotates and operative to short-circuit portions of the resistance, a weighted lever, an electro-magnet at one end of the lever to release the lever when the magnet is energized, means for engaging the toothed wheel to rotate the drum, a cam shaped disk operated by the lever to permit 105

the operation of the engaging means and to disengage the same at a predetermined time, and means in connection with the last short-circuiting magnet for lifting the lever to release the engaging means as soon as the said magnet is energized.

47. The combination with an electric motor, of starting resistance therefor, resistance cut-out mechanism comprising a 10 rotatable shaft, a toothed wheel secured to the shaft, a contact drum rotatably mounted on the shaft, electro-magnets energized in succession as the drum rotates and operative to short-circuit portions of the resistance, a weighted lever, an electro-magnet at one end of the lever to release the lever when the magnet is energized, means for engaging the toothed wheel to rotate the drum, a cam-shaped disk operated by the 15 lever to permit the operation of the engaging means, a rod in connection with the last short-circuiting magnet operative to raise the lever and release the said engaging means, and means for maintaining the circuit for the 20 said last short-circuiting magnet independently of the position of the drum and there-

by holding the lever in said raised position after the said engaging means has been released.

48. The combination with a motor, of 30 motor accelerating mechanism comprising a rotatable contact drum, mechanical connections between the motor and contact drum for effecting the rotation of the latter, an automatic switch, sectional starting 35 resistance for the motor, accelerating magnets, their windings having one common terminal connection through the switch, and electrical circuits closed and opened through the said contact drum connecting the accelerating magnet windings with the main line in regular succession to effect the operation of the said magnets to short-circuit portions of the sectional resistance.

In testimony whereof, I have signed my 45 name to this specification in the presence of two subscribing witnesses.

ERNEST L. GALE, SR.
